(57) **CLAIM**

The ornamental design for a “camera,” as shown and described.

DESCRIPTION

FIG. 1 is a front perspective view of a camera showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a rear perspective view thereof, with the back plate buckle in an alternate position;

FIG. 10 is a front perspective view of the camera with an unclaimed base portion; and,

FIG. 11 is a front perspective view of the camera with an unclaimed base portion, with the back plate buckle in an alternate position.

The broken lines illustrate environmental structure and portions of the camera which form no part of the claimed design.
